UNITED STATES PATENT OFFICE.

FREDERICK CHARLES BLYTHE, OF SOUTHSEA, ENGLAND.

PROCESS FOR THE DISTILLATION OF BITUMINOUS COAL.

No Drawing.

Application filed March 28, 1921. Serial No. 456,197.

To all whom it may concern:

Be it known that I, FREDERICK CHARLES BLYTHE, a subject of the King of England, residing at Southsea, Hants, England, have 5 invented certain new and useful Improvements in a Process for the Distillation of Bituminous Coal, of which the following is a specification.

My invention relates to a process to increase the yield of hydrocarbon oils by distillation of bituminous coal. It has for its purpose to avoid or hinder the cracking of the oils, thus decreasing the amount of the permanent gas which is produced by the ordinary system at the expense of the liquid hydrocarbons.

According to my invention I add to bituminous coal a certain amount of heavy hydrocarbon oils such as for example petroleum, kerosene, shale oil, heavy tar oil which may be obtained in this process and then heat and distil under pressure which can be regulated so as to yield from the coal, a large proportion of hydrocarbon oils and 25 a small proportion of permanent gas.

The coke or pitchy matter left in the retort may be used in any usual way.

In carrying out this process, I mix a small proportion of hydrocarbon oil with the bituminous coal in a crushed ground or small state, a convenient proportion being about five or ten parts of the hydrocarbon oil to one hundred parts of the coal but it must be understood that I do not limit the quantity 35 to this but more or less than this quantity or proportion of the hydrocarbon oil may be used.

I then heat gradually in a closed vessel or still made of any suitable material such as 40 iron so that the pressure inside the still rises. The pressure is regulated according to the temperature desired in the still. A convenient pressure is about 60 pounds to the square inch but this pressure may be varied up or 45 down according to the desired result. The temperature in the still is gradually raised to about 350° centigrade and then upwards to about 500° centigrade or between these points but this temperature may be exceeded 50 so as to drive off more of the hydrocarbons, or I apply such necessary heat by means of steam superheated, with or without external heat.

A convenient form of still is a cylinder or 55 a tube with an agitator or with a worm or spiral agitator moving the mixture forward

to the discharge end but any ordinary still of suitable material such as iron may also be used with or without an agitator.

The volatile products which distil off under pressure are cooled and condensed as far as practicable and any gas that does not condense may be used for burning.

The presence of the hydrocarbon oil mixed with the bituminous coal causes a more uniform softening or melting of the volatile constituents of the coal and generally acts as a carrier of such constituents and the pressure during the distillation prevents to a large extent the formation of permanent gas.

The hydrocarbon oil so added to the coal will also distil over to a large extent and be recovered with the hydrocarbon oils from the coal but no claim is made in this invention of the distillation of hydrocarbon oil alone under pressure.

In the process as above described the heavy hydrocarbon oils act as a kind of regulator of the destructive distillation of the bituminous coal, whilst the pressure applied to the mixture allows of a more intimate contact thus greatly facilitating the action of the regulator. When this action has taken place, it is not necessary to distil under pressure and the distillation can be effected under atmospheric pressure or under a vacuum. Therefore according to a modification of my process, I add to the coal the necessary hydrocarbon oil and heat the mixture as above described and after a suitable time, 90 for example when the desired temperature has been reached I release the pressure and I carry on the distillation of the volatile matter either under atmospheric pressure or in a vacuum.

What I claim is:

1. The method for the distillation of bituminous coal which comprises mixing the coal with a heavy hydrocarbon oil, heating the mixture under pressure, and then distilling the mixture at a pressure materially below 20 atmospheres to obtain a large proportion of hydrocarbon oils from the coal with a small proportion of permanent gas.

2. A process for the distillation of bituminous coal, which comprises mixing a small proportion of heavy hydrocarbon oil with bituminous coal in a finely divided state, then heating gradually in a closed vessel, increasing the temperature and pressure whereby the hydrocarbon oil acts as a regulator of the destructive distillation of the

bituminous coal, then releasing the pressure and completing the distillation of the volatile matter.

3. The method for the destructive distillation of coal which comprises heating the coal in a finely divided state under pressure in the presence of a heavy hydrocarbon oil regulator, and then distilling off the hydro-

carbon oil obtained from the destruction of the coal. ¹⁰

In testimony whereof I have affixed my signature in presence of two witnesses.

FREDERICK CHARLES BLYTHE.
